R. E. DUPLESSIS

FASTENER SUPPLYING DEVICE

Filed Feb. 26, 1921

UNITED STATES PATENT OFFICE.

RENÉ E. DUPLESSIS, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-SUPPLYING DEVICE.

Application filed February 26, 1921. Serial No. 447,997.

To all whom it may concern:

Be it known that I, RENÉ E. DUPLESSIS, a citizen of the United States, and resident of Beverly, in the county of Essex and State of Massachusetts, have invented certain Improvements in Fastener-Supplying Devices, of which the following description, in connection with the accompanying drawings, is a specification, like reference characters on the drawings indicating like parts in the several figures.

This invention relates to mechanisms for supplying fastenings, and is illustrated as embodied in a mechanism for supplying tacks to a hand tacker of usual type used in the manufacture of shoes.

In one form of such mechanism, commonly used in the lasting of shoes on a bed laster, tacks are automatically fed from a hopper into a raceway which feeds them to a co-operating raceway in the hand tacker, and a detent is provided at the end of each raceway, to retain tacks therein when the hand tacker is disconnected from the raceway on the feed mechanism; these detents being swung to idle position when the hand tacker is replaced. A difficulty found in using this and similar mechanisms is that when the hand tacker is removed, the shanks of the lowest tacks in the feeding raceway are left projecting, so that they readily become bent, in removing or replacing the hand tacker, or accidentally during its use. When a tack is so bent it will either jam the raceway until removed, or fall into the spill pan below the raceway. Accordingly, the tacks caught by the spill pan are ordinarily junked.

An object of this invention, accordingly, is the improvement of mechanisms of this character so as to prevent the protrusion of the shanks of fastenings from the feeding raceway, and an important feature thereof is to be found in a novel organization comprising an improved form and arrangement of detent adapted to restrain fastenings in a raceway, and means to move it longitudinally thereof to push the fastenings back from the open end.

Further features are to be found in various combinations and specific construc-

tions of parts hereinafter described and claimed, and shown in the accompanying drawings, in which—

Fig. 1 is a side elevation of a hand tacker 55 removably mounted on a feeding raceway;

Fig. 2 is an enlarged side elevation, and Fig. 3 is a top plan view, showing the joint between the tacker and the raceway;

Fig. 4 is a side elevation, and Fig. 5 is a 60 perspective, of the end of the tacker raceway; and

Fig. 6 is a perspective of the detent and its actuating mechanism.

A hand tacker 10, of usual construction, 65 is illustrated in Figs. 1 to 3 as removably connected to the lower end of a raceway 20, from which it is supplied with tacks. A hook 12 on the tacker is supported by a pin 22 on the raceway, and enters between plates 24, to align the raceway 14 of the hand tacker with the feeding raceway 20. When the tacker is removed, a detent 16 closes the upper end of raceway 14; when it is replaced, detent 16 is moved to idle position by a cam 75 surface 26. A pin 17 is rigidly mounted on the raceway 14, as shown in detail in Fig. 5, by a support 18, held by a clamp screw 19.

As shown clearly in Fig. 6, a finger-like detent 30 is provided to close the lower end 80 of raceway 20 when the tacker 10 is removed. This detent is in the form of a bell-crank lever, and has a pointed end 32 to project into the raceway to engage the shank of the endmost tack. It is provided with a slot 34, 85 which engages a fulcrum 36 carried by a fixed bracket 38. A spring 40, engaging the fulcrum 36 and a pin 42 carried by the detent, constantly urges point 32 into the raceway. The bracket 38 is secured to raceway 90 20 by a bolt and nut 44.

The detent 30 is provided with a second slot 46 at right angles to the first and engaging a pin 48 carried by a lever 50 fulcrumed on bracket 38 at 52. Lever 50 is 95 rocked in one direction by a plunger 54 carrying a pin 56 which enters a slot 58 in lever 50. It is rocked in the other direction by a spring 60, which constantly urges plunger 54 outwardly.

Plunger 54 carries a head 62, having a surface 64 which is engaged by pin 17 on

- the hand tacker, and which is approximately normal to the arc described by pin 17 when hook 12 is placed over pin 22, and the tacker is lowered into the position shown in Fig. 5. 1. Head 62 slides on a projection 66 formed on bracket 38.
- 10 In operation, when the tacker is removed, plunger 54, previously restrained by engagement of head 62 with pin 17, is automatically moved to the left by spring 60. Pin 56, moving with plunger 54, rocks lever 50 in a clockwise direction, as viewed in Fig. 6, so that its inner end, carrying pin 48, moves toward the raceway. Detent 30 accordingly 15 moves in the same direction under the influence of spring 40. This causes the end 32 of detent 30 to move in front of the tack at the extreme end of the raceway. Pin 48, as it continues to move, carries detent 30 bodily 20 rearward, this movement being permitted by the pin-and-slot mounting 34, 36. By following the path of pin 48, it will be seen that the rocking motion of detent 30 and the inward movement of its end 32 are at a 25 maximum at the beginning of the movement, and quickly approach zero as the motion of pin 48 becomes more nearly parallel to raceway 20. Thus, while the two motions of detent 30 actually overlap, the effect is the 30 same as if detent 30 were first rocked to insert the pointed end 32 into the raceway approximately at right angles to the raceway, and then moved bodily lengthwise of the 35 raceway to take the tacks upwardly into the raceway. This motion is reversed when the tacker is replaced.

At T, Fig. 6, is shown a tack with its head in raceway 20, and its shank projecting therefrom. By the above-described movement of detent 30, this tack is pushed back into raceway 20 upon removal of tacker 10, far enough so that its shank does not project from the open end of the raceway. Thus it is impossible for it to become bent, and 45 jam the raceway.

While I have described in detail one form of my invention, showing it embodied in a feeding raceway for a hand tacker, it is not the intention to limit its scope thereby. Obviously it is feasible to substitute a detent similar to the novel detent 30 for the one shown at 16, and the claims, except where specifically limited otherwise, are intended broadly to cover the embodiment of my invention in raceways of any type.

Having described my invention, what I claim as new and desire to secure by Letters Patent of the United States is:

- 1. In a device for supplying fastenings, in combination, a raceway for fastenings, a detent arranged to be rocked to retain fastenings therein, a spring to rock said detent into the raceway, a pin-and-slot fulcrum for the detent, and an actuating lever connected to the detent by a pin-and-slot connection

for allowing the spring to rock the detent into the raceway, and for moving the detent longitudinally of the raceway.

2. In a device for supplying fastenings to a removable fastening-inserting member, in combination, a two-part raceway for fastenings, a detent to retain fastenings in one part thereof, a plunger to be engaged by the other part thereof to move the detent longitudinally of the raceway to an idle position, and a spring to move the plunger and detent longitudinally of the raceway to active position which said member is removed.

3. In a device for supplying fastenings to a removable fastening-inserting member, in combination, a raceway for fastenings, a detent to retain fastenings therein, and a lever rocked by removal of said member to move the detent longitudinally of the raceway.

4. In a device for supplying fastenings to a tool removably mounted on a support, in combination, a two-part raceway for fastenings, a member movable to engage the fastenings in one part thereof, an arm arranged to be engaged by the other part of said raceway to hold said member inactive, and a spring moving said member upon removal of the tool for forcing the fastenings longitudinally of the raceway away from the end thereof.

5. Means for supplying fastenings to a removable device comprising a raceway for fastenings, a detent constructed and arranged to close the end of said raceway, and means rendered operative by the removal of the device to which fastenings are supplied to move said detent lengthwise of the raceway to move the fastenings longitudinally thereof away from the end of the raceway.

6. In a mechanism for supplying fastenings to a removable device, in combination, a raceway for the fastenings, and means actuated by removal of said device to close the end of the raceway and move the fastenings away from said end.

7. In a mechanism for supplying fastenings to a removable device, in combination, a raceway for the fastenings, and means operated by the removal of said device to move the fastenings longitudinally of the raceway away from the end of the raceway which is left open by removal of said device.

8. In a mechanism for supplying fastenings to a removable device, in combination, a raceway for feeding fastenings to said device, a detent, and means actuated by the removal of said device to cause the detent to move the fastenings rearwardly in the raceway thus preventing protrusion of the shanks of the fastenings beyond the raceway.

9. In a mechanism for supplying fastenings to a device removably connected thereto, in combination, a raceway for feeding fastenings to said device, and means operated

by the removal of said device for moving the fastenings rearwardly in the raceway thereby preventing the shanks of the fastenings from protruding from the raceway 5 when said device is disconnected.

10. A fastening-supplying device comprising a raceway and a member mounted to be moved into the raceway and away from the end thereof, said member being 10 arranged to engage the shanks of fastenings in the raceway thereby pushing the fastenings away from the end of the raceway.

11. Means for supplying fastenings to a removable device comprising a raceway and 15 a member mounted at the extreme end of the raceway automatically operative to close the end of the raceway and to move the fastenings therein away from the end of the raceway when the device to which the fastenings 20 are supplied is removed.

12. A tack-feeding device comprising a raceway for a succession of tacks, a pivotally-mounted member arranged to be rocked to close the raceway and to move a tack at 25 the end of the raceway away from the end thereof, and spring-operated means to rock said member and to move it lengthwise of the raceway.

13. A tack feeding device comprising a feed raceway, a removable co-operating feed member at the end thereof, and a tack-retaining device comprising a raceway-closing finger constructed and arranged to move the tacks longitudinally of the raceway away 30 from the end thereof, said member and said device being constructed with co-operating parts to insure closing of the raceway and moving the tacks therein when said member is removed.

40 14. A tack-feeding device comprising a feed raceway, a removable member at the end thereof, and a tack-retaining device comprising a pivotally mounted raceway-closing finger constructed and arranged to 45 be rocked to move the tacks longitudinally of the raceway away from the end thereof, said member and said device being constructed with co-operating parts to insure that said member is rocked, thereby closing 50 the raceway and moving the tacks therein, when said member is removed.

15. A tack-feeding device comprising a feed raceway, a removable co-operating feed member at the end thereof, and a tack-retaining device comprising a raceway closing finger constructed and arranged to move the 55

tacks longitudinally of the raceway away from the end thereof, said member and said device being constructed with co-operating parts to move said finger to open and close 60 the raceway and move the tacks therein.

16. A tack-feeding device comprising a feed race-way, a removable member at the end thereof, and a tack retaining device including a finger arranged to be rocked to 65 and from position in the raceway to hold or release the tacks and a sliding plunger to rock the finger back and forth, in combination with a spring urging the plunger forward to rock the finger into the raceway, 70 said member being constructed and arranged when attached to engage the plunger to compress the spring and rock the finger to release the tacks and when removed to allow the spring to operate. 75

17. In a fastening-supplying device, in combination, a raceway for fastenings, a detent constructed and arranged to close said raceway and means for moving said detent first inwardly approximately at right angles 80 to the raceway into engagement with the shank of a fastening and then rearwardly in the direction of the length of the raceway to close the end of the raceway and to move the fastenings rearwardly longitudinally of the 85 raceway.

18. A detent for controlling the passage of fastenings from a raceway comprising a finger having a fastening-engaging end, said finger being provided remote from its fastening-engaging end with a pair of slots arranged at right angles to one another. 90

19. A detent for controlling the passage of fastenings from a raceway comprising an elongated finger having a fastening-engaging end, said finger being provided remote from its fastening-engaging end with a pair of slots arranged at right angles to one another and with a projecting pin. 95

20. A tack-feeding device comprising a raceway arranged to receive a succession of tacks, and a pivotally mounted member at the extreme end of the raceway arranged to be rocked into engagement with the shank of the endmost tack in the raceway and thereafter to move lengthwise of the raceway to move the fastenings rearwardly in the raceway. 100 105

In testimony whereof I have signed my name to this specification.

RENÉ E. DUPLESSIS.

Certificate of Correction.

It is hereby certified that in Letters Patent No. 1,578,272, granted March 30, 1926, upon the application of René E. Duplessis, of Beverly, Massachusetts, for an improvement in "Fastener-Supplying Devices," an error appears in the printed specification requiring correction as follows: Page 2, line 78, claim 2, for the word "which" read *when*; and that the said Letters Patent should be read with this correction therein that the same may conform to the record of the case in the Patent Office.

Signed and sealed this 29th day of June, A. D. 1926.

[**SEAL.**]

M. J. MOORE,
Acting Commissioner of Patents.
